(57) **CLAIM**

The ornamental design for a landscape waterfall, as shown and described.

DESCRIPTION

FIG. 1 is a perspective view of a landscape waterfall illustrating water (shown in phantom) exiting an aperture and falling into a splash reducing material (also shown in phantom), the phantom lines forming no part of the claimed design.

FIG. 2 is a front side view of the landscape waterfall of FIG. 1.

FIG. 3 is a back side view of the landscape waterfall of FIG. 1, and ductwork shown in phantom on the back side view forms no part of the claimed design.

FIG. 4 is a left side view of the landscape waterfall of FIG. 1, and ductwork shown in phantom on the left side view forms no part of the claimed design.

FIG. 5 is a right side view of the landscape waterfall of FIG. 1, and ductwork shown in phantom on the right side view forms no part of the claimed design.

FIG. 6 is a top side view of the landscape waterfall of FIG. 1; and,

FIG. 7 is a bottom side view of the landscape waterfall of FIG. 1, and ductwork shown in phantom on the bottom side view forms no part of the claimed design.

The broken and phantom lines in the figures form no part of the claimed design.
